(57) **CLAIM**

The ornamental design for a watercraft dock, as shown and described.

DESCRIPTION

FIG. 1 is a perspective view of the watercraft dock in accordance with our new design, and shown in a condition of use.

FIG. 2 is a top plan view of the watercraft dock.

FIG. 3 is a bottom plan view thereof.

FIG. 4 is a left side elevational view thereof.

FIG. 5 is a right side elevational view thereof.

FIG. 6 is a front elevational view thereof; and,

FIG. 7 is a back elevational view thereof.

The broken lines depicting a watercraft show environmental structures which forms no part of the claimed design. The broken lines on the top surface of the watercraft dock illustrate a texture on the watercraft dock which forms a part of the claimed design.
